UNITED STATES PATENT OFFICE

148,124

DESIGN FOR A MICROSCOPE

John T. Armbruster, Niagara Falls, N. Y., and Charles W. Barton, Fort Erie, Ontario, Canada, assignors to American Optical Company, Southbridge, Mass., a voluntary association of Massachusetts

Application May 23, 1946, Serial No. 130,002

Term of patent 14 years

(Cl. D57—1)

To all whom it may concern:

Be it known that we, John T. Armbruster and Charles W. Barton, citizens of the United States of America, residing at 237 74th Street, Niagara Falls, and Fort Erie, in the county of Niagara and Province of Ontario, and State of New York and Dominion of Canada, respectively, have invented a new, original, and ornamental Design for a Microscope, of which the following is a specification, reference being made to the accompanying drawing, forming a part thereof.

The single figure in the drawing is a perspective view of a microscope showing our new design, the opposite side presenting substantially the same appearance as the side shown.

The characteristic features of our new design

reside in the portions shown in full lines in the drawing.

We claim:

The ornamental design for a microscope, substantially as shown and described.

JOHN T. ARMBRUSTER.
CHARLES W. BARTON.
